UNITED STATES PATENT OFFICE

HOWARD J. BROWNSBERGER AND HARRY E. McCONNELL, OF TOLEDO, OHIO

SHAVING BRUSH

Application filed September 11, 1923. Serial No. 662,048.

This invention relates to magazine brushes.

This invention has utility when incorporated in self lathering brushes more particularly as adapted to shaving.

5 Referring to the drawings:—

Fig. 1 shows an embodiment of the invention in use, parts being broken away to show the delivery duct.

10 Fig. 2 is a longitudinal section in perspective of the brush of Fig. 1 and

Fig. 3 is a showing of the brush magazine receiving a charge, parts being broken away.

15 Cluster of bristles 1 may be assembled into a fixed grouping with each other by rubber anchoring means 2 housed by shell 3. Centrally disposed in this group of bristles 1 and anchored by the anchoring means 2 is nozzle 4 having flexible duct terminus 5 as a delivery opening for lather promotion ingredients as liquid shaving soap or paste. 20 The delivery portion of this duct 5 is remote from the anchoring means 2 and thereby effects supply directly into the flexing lather forming and lather applying portions of the 25 bristles. As this duct 5 is flexible, even in vigorous use of the brush, there is not perceptible to the flesh of the user any detection of this duct 5 in the bristles. However, in brush manipulation the flexing of the bristles 30 1 likewise effects flexing of the duct 5, distributing the shaving soap as beyond the duct terminus while working back into the nozzle soap portions not discharged.

For convenience of manipulation this 35 brush shell 3 is provided with a handle member 6 of cylindrical form and having near one end thereof an externally threaded portion 7 to engage internally threaded portion 8 of shell 3 for thereby mounting detachably the 40 handle 6 as to the shell 3. Inwardly from this externally threaded portion 7 this handle or magazine member 6 has tapering portion 9 seated with the flare portion of the nozzle 4, and thereby providing a joint about internally threaded opening 10 from chamber 45 11 of this magazine member 6.

This magazine member or handle 6 remote from the opening 10 is provided with cap 12 having swivel connection by means of screws 50 13 in the member 6 which screws 13 extend

to engage groove 14 in the cap 12. This cap 12 has anchored therewith key stem 15 centered in the chamber 11 and extending toward the opening 10. This stem 15 is of keying or rectangular form and engages plunger 16 55 externally threaded to coact with internal threads 17 of the member 6. Accordingly any rotation of the cap 12 effects no travel of this cap 12 longitudinally of the member 6. However, through the stem 15 such rotation of the cap 12 in one direction urges the plunger 16 toward the opening 10, while rotation of this cap 12 in the opposite direction brings this plunger 16 toward the cap 12 and thereby increases the capacity of the 60 chamber 11 to a maximum.

With this chamber 11 enlarged by the movement of the plunger 16 toward the cap 12, this member 6 may be detached from the shell 3 and have the internal threads at the 65 opening 10 engaged by external threads 18 of a collapsible tube 19 or other supply device for discharging paste or other detergent into the chamber 11. When this charging of the magazine member 6 is effected, the 70 supply 19 may be removed and the shell 3 attached. The brush is now in condition for storing or use. If stored it is in condition for immediate use as may be desired. According to the nature of the supply of 75 detergent the bristles 1 may or may not be moistened. Slight rotation of the cap 12 80 may effect discharge through the flexible duct 5 of such quantity of the lather from the material as may be desired into the flexing lather applying terminal portions of said 85 bristles. As the use of the brush is completed the bristles 1 may be cleansed independently of washing away any material quantity of the lather producing material. 90 In fact such washing will only remove the material directly in the bristles, for the flexing nozzle or duct 5 due to brush manipulation is clean of material at its end portion, and accordingly the lather material is not 95 washed out thereof by cleansing the brush. The parts of the structure may be built of rubber, xylonite, bakelite or other sanitary material, and the structure thus produced is one commensurate with the life of the bristles 100

if not longer, in a form which will appeal to the trade.

What is claimed and it is desired to secure by Letters Patent is:—

- 5 In an elongated handle for a fountain brush comprising a cylinder of single thickness having a smooth exterior surface and provided on its interior surface with screw threads, a piston having threads on its
10 periphery engaging with said screw threads of the cylinder, a swivelled cap on the end of said cylinder, a square stem carried by said cap and slidably extending through a square hole in the center of said piston, and a dispensing nozzle on the other end of said cylinder as to which nozzle said cap is rotatable to actuate the piston along said stem.

In witness whereof we affix our signatures.

HOWARD J. BROWNSBERGER.
